OTHER PUBLICATIONS

Brian Lee Strother, U.S. Appl. No. 29/605,876, filed May 31, 2017, titled "Shoe Upper Element".

Primary Examiner — Dominic V Simone

(74) Attorney, Agent, or Firm — Lerner, David, Littenberg, Krumholz & Mentlik, LLP

(57)

CLAIM

The ornamental design for shoe upper element, as shown and described.

DESCRIPTION

FIG. 1 is a rear perspective view of my shoe upper element, according to my design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines shown in the drawings represent portions of the shoe upper element and exemplary footwear that form no part of the claimed design.

1 Claim, 6 Drawing Sheets
